UNITED STATES PATENT OFFICE

ERIK ARNFINN HALLGRIM KJÖRSTAD, OF LA ROCHELLE, FRANCE

APPARATUS FOR THE PREPARATION OF COOLING BRINE

Application filed November 18, 1927, Serial No. 234,163, and in France December 1, 1926.

The present invention relates to an apparatus for the preparation of a cooling brine by the use of ice and salt, said apparatus being chiefly adapted for use upon trawlers and like ships and more generally, upon all vehicles used for transporting food and other goods that is in all cases wherein the operative conditions differ from those of the usual stationary plants.

10 The known apparatus for the preparation of a cooling brine by the use of ice and salt is generally designed in such manner as to be mounted upon substantially stationary supports; but such apparatus are not 15 adapted to be used upon vessels, which are constantly subjected to pitching and rolling and like movements. In the usual apparatus, the liquid is free to oscillate and to follow up all such movements, thus resulting in the 20 formation of foam due to the motion of the liquid producing eddies, the brine falling down or splashing in the air. Furthermore, the supply or the discharge of the liquid may be interrupted when the vessel is inclined on 25 one side; the liquid then assumes a considerable kinetic energy when the vessel inclines on the other side, thus striking the walls of the apparatus and producing foam.

The apparatus according to the present 30 invention is of the type in which the cooling liquid flows through a mass of ice in suspension or floating in the liquid; said ice is maintained within the receptacle preferably by means of one or more grates at the bottom and a brine distributer or feeding device placed at the top; the liquid enters the column or mass of ice at one or more points, preferably situated below the upper level of 35 the ice column.

An important feature of the apparatus consists in that the ice column is surrounded with a partitioned receptacle adapted to contain a mass of liquid, the partitions or baffles 40 being so disposed as to divide the mass of liquid.

Some partitioning walls may be disposed vertically and others horizontally so as to limit or prevent horizontal and vertical 45 movements of the liquid, respectively, and to

provide means whereby the receptacle is kept constantly filled with brine.

Other features of the invention will be set forth in the following description with reference to the appended drawings which show, 55 by way of example, an embodiment of the invention:

Fig. 1 is a vertical section of one embodiment of the apparatus according to the invention.

Fig. 2 is a corresponding plan view.

Fig. 3 is a plan view of the lower grate.

Fig. 4 is a cross section on the line 4-4 of Fig. 3.

Fig. 5 is a plan view showing the various 65 parts of the lower grate.

The apparatus shown in the drawings comprises an internal receptacle A, adapted to contain ice, and provided at the bottom with a grate B (or several superposed grates), 70 and at the top with a hopper C for the introduction of ice; said hopper having a number of inlet orifices D for the liquid. The receptacle A is fitted within a second recipient E located itself within an outer receptacle F. 75 Between the walls of the receptacles A and F, and at a suitable height is arranged a partition I which is preferably horizontal. The ice is loaded through the hopper C, care being taken that the level of the ice is always above 80 the level of the liquid; the latter is supplied through the tube G into the space H between the said hopper and the recipient F. The space H preferably contains a suitable amount of salt.

The liquid supplied through the tube G rises to the level of the orifices D and passes through the latter into the said hopper and the receptacle A which, as above stated, are filled with broken ice to the level of the upper part of the said hopper. In this manner, the liquid, the ice and the salt are intimately mixed, and the formation of foam, which otherwise occurs when the ice, which must be constantly added to replace the melted ice, 95 drops into the liquid, or when the liquid falls upon the ice, is completely eliminated.

At the bottom of the receptacle A, the cooling liquid flows through the grate B into the receptacle E, thence above the upper edge of 100

the recipient E, and enters the recipient F, at the lower part whereof the cooling liquid is withdrawn through a discharge tube K. The said cooling liquid may also be discharged through a further tube L mounted close to the outlet of the grate B.

A considerable advantage afforded by the apparatus above described consists in the fact that the cooling liquid will circulate in a continuous manner irrespectively of the position or of the movements of the vessel at sea. I thus obviate the liquid falling or splashing in the air, so that no foam will be formed; I further obviate the irregular operation and accidental interruptions of the apparatus due to the provision of a large mass of liquid contained in the receptacles E and F and serving to compensate for the variations in the rate of flow of the liquid discharged from the grate B. Furthermore, since the chamber E is constantly filled with liquid, the grate B will always be submerged. Finally the mass of liquid in the receptacles E and F, which serves to compensate for the variations in the rate of flow of the brine and to maintain the orifice K constantly under a static head, will not be subjected to oscillations or will be subjected to oscillations of very small amplitude, due to the baffle disposition provided by the several recipients. In this manner, the differences of level due to the motion of the vessel and to the kinetic energy of the liquid in motion will be considerably reduced.

The liquid contained in the space H is always able to proceed into the hopper through one or more of the orifices in the row D, or, otherwise stated, a certain number of orifices of the set of orifices D will be passed through by the brine whereby the liquid will constantly circulate irrespectively of the inclination of the vessel.

The grates at the bottom and the distributor or feeding device at the top are so disposed that the liquid will flow downwardly and from the outside to inside, through the mass of ice; these conditions are found to be highly desirable for the proper operation of the apparatus.

The grates placed below the ice are arranged so that the cooling liquid will be uniformly distributed throughout the whole mass of the ice. For this purpose, the said grates preferably consist of a set of plates M—M₁—M₂ which are apertured at the centre; said plates are superposed and spaced apart by bars or slabs affording free passage to the brine. The size of the said plates may decrease from bottom to top, and the upper plate M need not be apertured at the centre. I may obviously employ any other known type of grates for this purpose.

Instead of introducing the salt to be dissolved into the liquid through the space H, I may saturate the cooling liquid by circulat-

ing the same through a separate receptacle, conduit, trough or the like containing salt, or by introducing the proper amount of a saturated salt solution into the brine. Some or all of the aforesaid means may also be combined.

Should the output of the apparatus exceed the normal rate of consumption, so as to keep the level of the liquid below a predetermined level, an overflow device may be required. Such an overflow P may be mounted at the top of the outer recipient, as shown in Fig. 1.

Obviously, the plant may be composed of a plurality of similar apparatus disposed in series or in parallel arrangement. When in series, the several apparatus are disposed in such manner that the static head due to the difference of levels in the successive apparatus, will cause the circulation of the liquid from one apparatus to the next.

The said invention is not limited to the constructional details herein specified. The number of receptacles may be greater than three. Their walls will always form a set of baffles so as to divide the mass of liquid in the proper manner. The distributor or like device for feeding the brine at the top and the grates disposed at the bottom may be of any other type, and for example the liquid supply orifices may consist of a grate of cylindrical, conical or any other shape.

Having now described my invention what I claim as new and desire to secure by Letters Patent is:

1. In an apparatus for the preparation of a cooling brine comprising an ice column adapted to be passed through by a salt solution, a receptacle in communication with and surrounding said ice column and adapted to contain a mass of brine, substantially vertical partition walls and a substantially horizontal partition wall in said receptacle, and means for withdrawing brine from said receptacle.

2. In an apparatus for the preparation of a cooling brine comprising an ice column adapted to be passed through by a salt solution, a number of receptacles in communication with and surrounding said ice column and fitted within one another, said receptacles being adapted to contain brine, means for withdrawing brine from said receptacles and a hopper for the ice at the upper part of the innermost receptacle.

3. An apparatus as claimed in claim 2 wherein said hopper has a row of inlet orifices for the brine.

4. In an apparatus for the preparation of a cooling brine comprising an ice column adapted to be passed through by a salt solution, a receptacle in communication with and surrounding said ice column and adapted to contain a mass of brine, substantially vertical partition walls and a substantially hori-

zontal partition wall in said receptacle, means for supplying the salt solution into the ice column above said horizontal wall and means for discharging the brine from said receptacle below said horizontal wall.

5. In an apparatus for the preparation of a cooling brine comprising an ice column adapted to be passed through by a salt solution, a number of receptacles in communication with and surrounding said ice column and fitted within one another, said receptacles being adapted to contain brine, means for withdrawing brine from said receptacles and means for discharging the brine at the lower part of the outer receptacle.
10. In an apparatus as claimed in claim 5, further means for discharging the brine at the lower part of the innermost receptacle, below the ice column.
15. In an apparatus as claimed in claim 5, further means for discharging the brine at the lower part of the innermost receptacle, below the ice column.

20. In an apparatus as claimed in claim 1, the provision of an overflow pipe immediately below said horizontal wall.

In testimony whereof I have signed my name to this specification.
